FOUNDRY FLASK

William Mellen Duncan, Alton, Ill., assignor to
 Duncan Foundry and Machine Works, Inc.,
 Alton, Ill., a corporation of Illinois

Application September 28, 1945, Serial No. 619,125

1 Claim. (Cl. 22—111)

1 This invention relates to foundry flasks and particularly to reinforcement of the sand therein. The art of making large metal castings has long included the use of the molding flask, a piece of foundry equipment generally, though not always, of two parts, namely, a cope or upper section and a drag or lower section. The cope and drag both contain molding sand and since the cope must be lifted from the drag, molding sand to be retained therein requires some sort of reinforcement. Numerous methods and devices have been used for this purpose but none have been fully satisfactory.

Heretofore attempts have been made to reinforce sand in a mold by embedding jagger bars or plates therein, but such arrangements have not proved satisfactory for the reason apparently that lines of cleavage form in the impacted sand along the faces of the reinforcing members. To overcome the adverse effects of cleavage lines, it has also been proposed to provide holes in the bars or plates. This, in theory, provided sand cylinders and interconnecting sand necks tending to hold the sand body more firmly in place in the cope. In practice, however, the vertical jolting or ramming of the sand seldom provides sufficient lateral thrust to cause the sand to flow laterally into the holes, and sand must be packed firmly enough to provide appreciable reinforcing effect.

The object of this invention is to obviate these defects and to provide an economical and more practical means for retaining molding sand in the cope of the molding flask.

The invention will now be described in more detail with reference to the following drawings, in which:

Figure 1 is a plan view of the cope of a molding flask provided with reinforcement in accordance with this invention;

Figure 2 is a cross section of an entire flask assembly along the indicated line 2—2 of Figure 1;

Figure 3 is a perspective view of a modified form of reinforcement; and

Figure 4 is a perspective view of another modified form of reinforcement.

This invention provides for the installation of a plurality of wire grills of metal supported on the cope portion of a molding flask and extending vertically from side to opposite side of said cope, these grills being of such design that their members offer little resistance to the inward flow of sand when it is rammed into the cope and whose open spaces are of such size that the sand

particles flow freely laterally upon impaction and thus embed the reinforcing metal lattice work into a homogeneous sand mass containing no lines of cleavage. These grills become an integral part of the mold in which they are embedded. They are arranged and designed so as to clear the pattern by an amount suited to the shape and weight of the casting to be made. The grill members provide a large area for the adhesion of the binding element incorporated in the sand and transforms the roof of the mold into a reinforced sand slab of high tensile strength.

Referring to Figures 1 and 2, 1 represents a metallic grill, a plurality of which are shown. 15 These grills extend vertically from side to opposite side of the cope 2 resting upon a drag 3. A pattern 4 is indicated in its relationship to the metallic grills in their installed position in the cope. The grill 1 is a metallic lattice-work of horizontal members 5 and vertical members 6, whose dimensions bear a definite relationship to the openings 7 they frame.

The present invention contemplates that the cumulative cross sectional area of the members 25 5 and 6 does not exceed one-half the total area of the grill 1. Such a grill provides sufficient free space for the sand to flow laterally upon impacting, ramming, or jarring. The sand particles meet little longitudinal resistance, and 30 hence flow so as to embed the grill 1, but when compacted cohere to such an extent that the mass is amply reinforced by the grill 1. Woven wire screening is the simplest form of such a metallic grill, but the longitudinal flow of the molding sand in the cope is better served by building a grill whose horizontal bars 8 are oval in section and deformed around square bars 9 mounted vertically as shown in Figure 3. As between these two types of grills, a variety of forms 35 40 of grills can be constructed to serve the purpose described.

Figure 4 shows a grill whose vertical members 15 and horizontal members 16 are both square in cross-section. Ease and practicality of construction, in conjunction with the necessary requirements of longitudinal flow and high retention as between sand and the grill, are accomplished here.

Where the vertical and horizontal members 45 are of different cross-sectional area or shape, the diameters of the members or the narrow dimension thereof, as shown in Figure 3, are preferably one-fourth or less of the maximum lineal dimension of a contiguous opening in the grill.

Where square members are used in building the grill a better approximation of the size of the members to the opening they frame is that wherein the cross corner measurements of the intersecting members are limited to one-quarter of the maximum lineal dimension of a contiguous opening. This measurement is indicated by line $x-x$ of Figure 4.

The spacing of grills 1 within the cope in order to support the sand to the optimum extent varies with the size and shape of the pattern and flask, as well as with the condition of the sand. So long as sufficient space to accommodate the ramming tools is left between the grills they cannot be arranged too closely together. At the other extreme, one grill is better than none. Consequently great latitude of choice exists as to the number and spacing of the grills 1.

The depth of sand in a cope is a function of the pattern shape, as well as the flask size. The larger the flask, the deeper must be the sand above the highest point on the pattern. Without adequate reinforcing the sand must be deep enough to form a natural arch. The grill makes possible the replacement of the cumbersome arch roof with a light reinforced slab. Much time, labor and material is saved by the lesser amount of sand that must be rammed.

It is understood, of course, that this invention is not limited to any particular size or shape of the individual grill members, that is, whether or

not they are deformed, similar, or unlike, except that such sizes and shapes bear the aforementioned relationships to the apertures they frame.

Having thus described the invention, what is claimed as new and desired to be secured by Letters Patent is:

The combination with a molder's flask of a metallic grill composed of interwoven wire members with diameters not exceeding one-fourth the maximum lineal dimension of a contiguous opening of the grill, said grill extending vertically of the flask and from side to opposite side of the cope portion of the flask and secured thereto, the interstices of said grill being open for the inflow of sand from both sides of the grill.

Certificate of Correction

Patent No. 2,460,218.

January 25, 1949.

WILLIAM MILLEN DUNCAN

It is hereby certified that errors appear in the printed specification of the above numbered patent requiring correction as follows:

In the grant, line 1, and in the heading and signature to the printed specification, name of inventor, for "William Mellen Duncan" read *William Millen Duncan*; and that the said Letters Patent should be read with these corrections therein that the same may conform to the record of the case in the Patent Office.

Signed and sealed this 16th day of August, A. D. 1949.
